UNITED STATES PATENT OFFICE.

UTLEY WEDGE, OF ARDMORE, PENNSYLVANIA.

TREATING ORES.

1,170,375.

Specification of Letters Patent.

Patented Feb. 1, 1916.

Application filed October 7, 1911. Serial No. 653,421. Renewed July 1, 1915. Serial No. 37,583.

To all whom it may concern:

Be it known that I, UTLEY WEDGE, a citizen of the United States, residing at Ardmore, Pennsylvania, have invented certain 5 Improvements in Treating Ores, of which the following is a specification.

The object of my invention is to provide a convenient, economical and effective process for causing the desulfurization, chloridizing 10 or like treatment of metallic ores or other metal-containing bodies (hereinafter, for convenience, referred to as "ore") in such a way as to prevent contamination of the gas or gaseous compound driven off during the 15 roasting or calcining operation. This object I attain by subjecting the ore to a two-stage treatment, the heat for the final stage of the treatment being derived from the products 20 of combustion from coal, coke, fuel oil, natural gas, wood, or other carbonaceous fuel, and the heat for the first stage of the operation being derived from, or maintained or assisted by heated air or gas other than the 25 combustion gases, such air or gas being, by preference, heated by means of the waste combustion gases employed in the second stage of the process. By this means the air or gas which, in any event, is required for the oxidation or other preliminary treatment 30 of the ore whereby a gas or gaseous compound is evolved therefrom, does not contaminate such gas or gaseous compound so as to prevent the subsequent utilization of the same, as for instance, in the manufacture 35 of sulfuric acid, or other commercial use, while at the same time provision is afforded for the application of a higher degree of heat by direct access of the gases arising from the combustion of the fuel to the 40 ore in the subsequent treatment of the latter for the purpose of effecting complete desulfurizing or other desired action thereupon.

In the accompanying drawings Figure 1 is a vertical sectional view of a furnace constructed in accordance with my invention and carrying out my improved process; Fig. 2 is a top or plan view of said furnace; Fig. 3 is a section on the line *a*—*a*, Fig. 1; Fig. 4 is a vertical sectional view illustrating a modified form of furnace embodying my invention, and Fig. 5 is a top or plan view of the same.

The furnace shown in Fig. 1 is of the well known Wedge type and comprises a series 45 of superposed hearths with a central rotating shaft, the latter being provided with

arms having stirrers or rabbles thereon, whereby the material under treatment is fed over the hearths in succession and falls from hearth to hearth of the series from top 50 to bottom of the furnace. The improved furnace, however, is divided into upper and lower sections by means of a flue 1 through which the products of combustion from the lower section of the furnace escape to a suitable stack 2, an air or gas heating flue 3 being located in proximity to this escape flue, which flue communicates through a flue 4, in the side wall of the furnace or other convenient location, with the lowermost hearth of 70 the upper section of the furnace.

The products of combustion from a suitable fuel supply enter the lowermost treating chamber of the lower section of the furnace and pass upwardly through the successive treating chambers of said lower furnace section, finally escaping through the flue 1 to the stack 2. The walls of the flue 3 become highly heated by contact with the 75 lower section of the furnace and air or gas entering said flue 3 has a correspondingly 80 high degree of heat imparted to it so that when it finally enters the lowermost treating chamber of the upper section of the furnace 85 its temperature will be high enough to effect the desired roasting or other treatment of the material in said upper section of the furnace, the evolved gases or mixture finally 90 escaping through a suitable outlet flue 5 communicating with the uppermost working chamber of said upper section of the furnace.

The ore to be treated is deposited upon the roof of the furnace and is directed by means of a suitable feeder 6 onto the uppermost hearth of the upper furnace section and passes therefrom onto and over the successive lower hearths of said upper furnace section, finally passing through the lowermost hearth thereof onto the uppermost hearth of the lower section and then onto the successive lower hearths of the same until it finally reaches the discharge 100 7, any suitable means being employed for trapping the passages between the upper 105 and lower sections of the furnace to prevent the passage of the gases of combustion from the lower to the upper section.

In passing over the hearths of the upper section of the furnace the ore is therefore 110 subjected to such heat as is necessary to effect the desired treatment of the same, the

ore not being subjected to the action of the heated products of combustion until it passes into the lower section of the furnace through whose treating chambers a circulation of such heated products of combustion is maintained. While, therefore, the ore is subjected eventually to a sufficiently high temperature to complete its desulfurization or other desired final treatment the preliminary operation is effected without the direct contact with the gases of combustion, and consequently the gas or gaseous compound produced in the preliminary operation is kept free from contamination with the products of combustion and consequently in proper condition for its subsequent utilization.

The lower section of the furnace may be combined with any desired form of fireplace or fireplaces for the burning of carbonaceous fuel, although I prefer for this purpose to use one or more oil or gas burners 9, communicating with the lowermost treating chamber of the furnace. Any desired arrangement of pipes or flues may be adopted for effecting the heating of the incoming air or gas supply by means of the outflowing volume of the products of combustion, or an arrangement similar to the well known "Siemens" regenerator may be employed for this purpose. If desired, also, the furnace structure in which the final treatment of the ore is effected may be separate from the structure in which the preliminary or roasting treatment is carried on, and in Figs. 4 and 5 I have illustrated such a construction of the furnace. Between the two members of this furnace is interposed a structure 10 containing the gas and air flues 1^a and 3^a, the uppermost treating chamber of the final section of the furnace communicating with the gas flue which discharges through a stack 2^a and the air or gas heating flue 3 communicating with a pipe 11 similar to the twyer pipe of an ordinary blast furnace

which communicates through branches 12 with the lowermost treating chamber of the preliminary member of the furnace, any suitable form of conveyer 13 serving to carry the material discharged from the lowermost treating chamber of the preliminary member of the furnace to the uppermost treating chamber of the final member.

Although, for purpose of economy, it is advisable to heat the air or gas with which the material is treated during the first stage of the process by means of the waste products of combustion escaping after the treatment of the material during the second stage of the process, such heating may be effected by independent means, if desired.

I claim:

The mode herein described of treating ores, which consists in subjecting the same to a two-stage treatment, feeding the ore over one or more hearths in each stage of the treatment, conveying the ore from the primary to the secondary stage of the treatment without permitting passage of products of combustion from the secondary to the primary stage, supplying heated air to the ore during the primary stage of treatment in order to effect ignition of the combustible constituents of the ore, supplying to the ore during the secondary stage of the treatment products of combustion derived from fuel independent of that constituting the furnace charge, and utilizing the escaping products of combustion from the secondary stage of the treatment to heat the air employed for effecting combustion of the charge in the primary stage.

In testimony whereof, I have signed my name to this specification in the presence of two subscribing witnesses.

UTLEY WEDGE.
